THROTTLE CONTROL

Charles W. Finkl, Evanston, Ill.

Application May 31, 1947, Serial No. 751,531

4 Claims. (Cl. 74—501)

1

This invention relates to a throttle control and more particularly to an improvement in an automatically closing, hand-operated throttle control for an internal combustion engine.

The invention as shown in the accompanying drawings is particularly adapted for use with an outboard motor boat. However, it will be understood that this throttle control could be used, without departing from the inventive concepts thereof, in conjunction with any one of several other types of engines having hand controlled throttles.

It is an object of this invention to provide a throttle control which under normal operating conditions will automatically close the throttle associated therewith when the operator removes his hand from the control.

It is another object of this invention to provide a throttle control having a throttle lever which can be selectively locked instantly by the operator in a plurality of open-throttle positions.

It is another object of this invention to provide a throttle control having a throttle lever with means associated therewith which will control a Bowden mechanism wire secured to a throttle without bending the Bowden control wire between the end of the Bowdenite casing and the throttle lever.

It is a further object of this invention to provide a throttle control having constantly available means for adjusting the retractile movement, fully retracted limit, and open-throttle positions of the throttle lever thereof without said means becoming obstructions to the free operation of the throttle lever.

It is still another object of this invention to provide a throttle control which may be mounted on either side of the operator and operable in either position without alteration or adjustment of any of the parts thereof or method of operation.

Other objects and advantages will be apparent from a consideration of the following specification, claims and drawings, of which there is one sheet in which like reference characters are used to designate like parts, and in which:

Figure 1 is a side elevational view of a speed boat hull and motor showing the invention as associated therewith;

Figure 2 is an enlarged side elevational view of the invention showing same from the side opposite that of Figure 1;

Figure 3 is a view of the invention looking from below the invention;

Figure 4 is a view similar to Figure 2 with the invention partially disassembled;

2

Figure 5 is a side elevational view of a portion of the invention; and

Figure 6 is a side elevational view of another portion of the invention.

Illustrated in Figure 1 is a speed boat outfit comprised generally of a hull 2 and an outboard motor 4. The invention, a throttle control (indicated generally at 6) for motor 4, is shown attached to hull 2 and is connected to throttle lever 10 of motor 4 by a Bowden mechanism wire 8.

The casing of the throttle control 6 is comprised of a pair of identical right and left hand castings 12 which fit together to form a mounting means for the movable parts of the invention. Each of the castings 12 are provided with body portions having outwardly extending portions 14 which are in turn provided with aligned notches 16 which form finger grip means for the operator. Each of the portions 14 is provided with a groove 18 along the length thereof. Grooves 18 are aligned and provide an aperture extending from the outer ends 20 of portions 14 to the inner cut-out portions 22 of castings 12. Centrally, each of the castings 12 is provided with a cut-out portion 22 (Figure 4) so that movable means may be operably mounted within castings 12 when the castings are positioned together as in Figure 3. Portions 22 are enclosed by the outer walls 24 of castings 12 except for a distance adjacent the rearward sides of portions 14 where walls 24 do not enclose portions 22 but are deleted and thus provide an aperture through which means to be described herein-after may extend from within castings 12 when they are assembled.

Walls 24 of castings 12 are provided, near the bottom thereof, with adjoining grooves 26 which form an aperture extending rearwardly from portions 22 through walls 24. Grooves 26 are provided with enlarged portions 28 at the outer ends thereof. In the upper portion of walls 24 are provided another pair of adjoining grooves 30 having outer enlarged portions 32. Grooves 30, like grooves 26, extend rearwardly from portions 22 through walls 24. Aligned grooves 34 and 36 are formed in the walls 24 of each of the castings 12. Grooves 34 provide an aperture extending rearwardly through walls 24 and grooves 36 adjoin to form an aperture through the inwardly extending portions 38 of walls 24. Further, walls 24 are provided with a series of closely spaced adjoining grooves 40 which form apertures which extend generally downward through walls 24 from portions 22. A series of aligned pairs of apertures 42 ex-

tend through walls 24 of castings 12. One aperture 42 of each pair may be threaded internally so that a screw extending through the aperture aligned therewith may be turned into engagement with the threaded aperture to rigidly secure the castings 12 together as shown in Figure 3. A second series of pairs of aligned apertures 44 extend through walls 24 and screws or other suitable means may extend therethrough to secure throttle control 6 (Figure 1) to hull 2.

A lever 46 extends from within castings 12 through the aperture provided where walls 24 are deleted as described hereinbefore. Lever 46 is rotatable about the axis of bolt 48 which extends through aligned horizontal apertures formed in castings 12 and lever 46 near the centers thereof. Lever 46 is provided with aligned apertures 50 and 52 extending along the length and generally through the center thereof. A rod 54 extends through apertures 50 and 52 and is provided with a lower reduced portion 56 which may be selectively positioned in any one of the apertures formed by grooves 40 by rotating lever 46 to align portion 56 with one of said apertures and pressing rod 54 downwardly through lever 46. Rod 54 has an enlarged upper portion 58 which forms a finger button to facilitate the moving of rod 54 downwardly by the operator. Lever 46 is provided with a cutout portion 60. A cotter pin 62 extends through an aperture in rod 54 adjacent the upper wall of portion 58 and a compression spring 64 is telescopically positioned around rod 54 between pin 62 and the lower wall of portion 60. Spring 64 is provided to constantly urge rod 54 upwardly when portion 56 thereof is positioned in any one of the apertures formed by grooves 40.

In the upper end of the aperture formed by grooves 40 is positioned a rotatable rod 66 which has an enlarged upper end 68 abutting the upper ends of portions 14 and a threaded hole 70 extending upwardly along its axis from the lower end thereof. In the lower portion of the aperture formed by the grooves 18 is positioned a rod 72 movable along its axis in said aperture and having a reduced, threaded upper end 74 turned into engagement with threaded hole 70 of rod 66. Rod 72 has an aperture 76 extending through the lower end thereof.

A tension spring 78 has its upper end hooked through aperture 76 of rod 72 and its lower end hooked through aperture 80 formed in the forward side of lever 46 and below the center of bolt 48. Spring 78 tends to rotate lever 46 in a counter-clockwise direction around the axis of bolt 48 and tends to hold rod 54 in a lower position with portion 56 thereof in one of the apertures formed by grooves 40 by increasing the frictional engagement between portion 56 and the walls of said aperture. This function of spring 78 makes it possible to set lever 46 in any one of several open-throttle positions and maintain said position without manual control as the action of spring 78 will prevent the upward movement of rod 54 by spring 64 until the frictional engagement of portion 56 and the aperture is reduced by manual movement of lever 46. The tension of spring 78 is adjustable by manually turning rod 66. If hole 70 is provided with a conventional right hand thread, clockwise turning of rod 66 will pull rod 72 upwardly stretching spring 78 and increasing the tension thereof on lever 46. Counter-clockwise turning of rod 66 will, of course, decrease the tension of spring 78. In this manner means for

holding the throttle lever in any one of several open-throttle positions is provided and means for selectively adjusting the tension of the throttle lever spring is provided.

The linkage between lever 46 and Bowden mechanism 8 (Figure 1) is comprised of identical pistons 82 movable in the apertures formed by grooves 26 and 30. Pistons 82 are drivingly connected by links 84 to lever 46. Links 84 are pivotally connected to lever 46 by pins 86 extending through aligned apertures in links 84 and lever 46. The opposite ends of links 84 are pivotally connected to pistons 82 by pins 88 which extend through apertures in links 84 which are aligned with apertures 90 (Figure 6) of pistons 82. Pistons 82 are provided with apertures 92 extending along the axis thereof and Bowden control wire 94 of Bowden mechanism 8 is positioned in one of said apertures 92 and rigidly secured therein by set screws 96 which are turned into threaded apertures 98 which extend outwardly from apertures 92.

In Figure 4 a wire 94 is shown associated with each of the pistons 82 for clarity. However, it will be understood that only one will be used in actual operation and the provision of the two pistons 82, one connected to lever 46 on one side of bolt 48 and the other on the opposite side thereof, is made necessary as the throttle levers 46 (Figure 1) on some motors operate in one direction and on others in the opposite direction. Thus, with the use of two pistons 82, one of which is retracted when the other is extended, makes it possible to operate the various types of throttles by selectively connecting wire 94 to pistons 82. Further, the operation of lever 46 remains the same under any of these conditions.

The Bowden casing 100 of the Bowden mechanism wire 8 is rigidly secured to control 6 through its connection with cylindrical sleeve 102. Sleeve 102 is provided with an aperture 104 extending along its axis in which the end of casing 100 is positioned. Sleeve 102 is longitudinally split as at 106 (Figure 5) and thus means for squeezing sleeve 102 to frictional engagement with casing 100 is provided. Sleeve 102 is positioned within either of the apertures formed by grooves 26 and 30, depending on which piston 82 wire 94 is secured to, and is provided with an enlarged end 108 which is positioned in the enlarged portions 28 and 32 of grooves 26 and 30 in abutment with walls 24 adjacent the outer ends of grooves 26 and 30. Sleeve 102 is held in position by set screws 110 (Figure 2) extending through threaded apertures in walls 24 to the apertures defined by grooves 26 and 30. The longitudinal axes of sleeve 102, the end of casing 100 within sleeve 102, wire 94, the apertures defined by grooves 26 and 30, and the pistons 82 are coincidental and thus when wire 94 is pulled or pushed by either one of pistons 82, wire 94 will not be bent between casing 100 and pistons 82. If wire 94 were directly connected to the lever 46, as is commonly done, the connection therebetween would travel in an arc around the center of bolt 48 which would cause constant bending of wire 94 and eventual destruction thereof.

Limit means for the counter-clockwise rotation of lever 46 is provided in the form of a rod 112 which extends from without walls 24 through the apertures defined by grooves 34 and 36 to its inner end 114 which abuts lever 46 above bolt 48. Rod 112 may be moved along its axis to vary

the distance lever 46 may be rotated in a counter-clockwise direction and upon adjustment to the desired position may be secured there by turning set screw 116 (Figure 2) into frictional engagement therewith. Set screw 116 extends through a threaded aperture in walls 24 to the aperture formed by grooves 34.

Slots 118 and 120 are cut through the sides of one or both of the castings 12 to provide ready access to the pistons 82 and associated parts when in certain positions. This makes possible certain adjustments without separating castings 12.

The invention described above provides a throttle control which does not continually bend the Bowden control wire 94 as said wire is moved by the lever 46. Further, by providing linkage means between lever 46 and wire 94 both above and below the bolt 48, the control can be used with any motor regardless of which way the throttle thereof moves and the control because it has both upper and lower linkages may be placed on either side of the passenger compartment so as to accommodate both right and left handed operators. Further, the invention provides a safety mechanism for lever 46 inasmuch as portion 56 of rod 54 may be pressed down into any one of the pairs of grooves 40 to fix lever 46 in one position but as soon as lever 46 is moved, spring 64 will push rod 54 upwardly moving portion 56 out of the grooves 40 leaving lever 46 free to be moved counter-clockwise by spring 78 to closed position. This is possible because portion 56 is held in frictional engagement with the walls of grooves 40 by spring 78 against the weight of spring 64 and any movement of lever 46 will reduce or destroy this friction. The adjustment means for spring 78 is provided with a non-rising stem to avoid this mechanism from being in the way during normal operating conditions. As described above, the invention provides a stroke adjustment for lever 46 which provides as accurate stroke adjustment as is possible.

While I have described my invention in considerable detail, I intend this description to be an example only, and not a limitation on my invention, to which I make the following claims.

I claim:

1. A control mechanism comprising a mounting means, a lever rotatably secured near its center to said mounting means, resilient means for rotating said lever in one direction, a Bowden mechanism adapted to be selectively secured to said mounting means above and below the center of said lever, and linkage means above and below the center of said lever for connecting said lever and the Bowden control of said Bowden mechanism for moving said control wire beyond the Bowden casing of said Bowden mechanism coaxially with said Bowden casing.

2. A control mechanism comprising a casing, a lever rotatably mounted near its center in said casing, resilient means to rotate said lever in one direction, a Bowden mechanism adapted to be selectively secured to said casing above and below the center of the lever, independent linkage means drivingly secured to said lever above

and below the center of the lever for connecting the Bowden control of said Bowden mechanism and the lever, and guide means for said linkage means formed in said casing for controlling the movement thereof to permit said control wire to only move coaxially in relation to that part of the Bowden casing of said Bowden mechanism adjacent the casing.

3. A control comprising a casing, a lever rotatably mounted near its center in said casing, a resilient means for rotating said lever in one direction, an adjustable stop means for limiting the rotation of said lever by said resilient means, means for adjusting the rotating force exerted by said resilient means, means cooperable with said casing for holding said lever in a fixed position, resilient means constantly urging the means cooperable with the casing out of cooperation therewith, a Bowden mechanism adapted to be secured to said casing above and below the center of said lever, and linkage means secured to the lever above and below the center thereof and designed to be secured to the Bowden control wire of the Bowden mechanism for moving same coaxially with that part of the Bowden mechanism secured to the casing.

4. In a control mechanism, a case means, a manually controllable lever mounted in said case and near the center thereof and rotatable substantially about its center to fully extended and fully retracted positions, adjustable resilient means constantly urging said lever to a fully retracted position, means mounted on said case means to adjust the fully retracted position of said lever, means carried by said lever and cooperable with the case means for holding said lever in any one of several positions between the fully extended and fully retracted positions thereof, slide means, guide means formed in said case means for positioning one of said slide means above and one below the center of rotation of said lever and to guide said slide means in a straight line, link means connecting each of the slide means with said lever one above and one below the center of rotation of the lever, a Bowden mechanism secured to said case means coaxially with the slide means, and means for securing the Bowden control wire of the Bowden mechanism to either of said slide means.

CHARLES W. FINKL.
